UNITED STATES PATENT OFFICE.

JOHN W. DARLEY, JR., OF BALTIMORE, MARYLAND, ASSIGNOR, BY MESNE ASSIGNMENTS, TO THE AMERICAN PIANO COMPANY, A CORPORATION OF NEW JERSEY.

AUTOPNEUMATIC MOTOR FOR SELF-PLAYING MUSICAL INSTRUMENTS.

No. 902,882.

Specification of Letters Patent.

Patented Oct. 27, 1908.

Application filed February 5, 1908. Serial No. 414,435.

To all whom it may concern:

Be it known that I, JOHN W. DARLEY, Jr., a citizen of the United States, residing at Baltimore, in the county of Baltimore City and State of Maryland, have invented certain new and useful Improvements in Auto-pneumatic Motors for Self-Playing Musical Instruments; and I do hereby declare the following to be a full, clear, and exact description of the invention, such as will enable others skilled in the art to which it appertains to make and use the same.

My invention relates to auto-pneumatic motors for self-playing musical instruments.

The object of my invention is to provide a simple device of this class in which the motors are inclosed in a dust proof case, presenting a neat appearance, and preventing the noise of the motor from being heard, the device being so constructed that the valves may be readily reached for cleaning and attention.

With these objects in view, my invention consists in the construction and combinations of parts as hereinafter described and claimed.

In the accompanying drawings—Figure 1 is a front view of my improved apparatus, the front of the box being removed. Fig. 2 is an end view of the same, partly in section, and Fig. 3 is a broken plan view of the same.

a represents a dust proof casing in which the motors are mounted, thus preventing them from collecting dust and preventing their noise from being heard, to the discomfort of the performer.

b represents the driving shaft of the motors, provided with a sprocket wheel c which drives the music rolls in the usual manner.

In Fig. 1 there are three of these motors shown, each one of them being a double motor, as indicated in Fig. 2. The shaft c is provided with three cranked portions, such as d, and to each of these portions is attached one end of a link e, the other end of which is pivoted to an arm f attached to the upper part of the movable member of the double bellows g. Pivoted attached to an ear on the arm e is a link h, the other end of which is attached to a sliding valve i.

The bellows g consists of a board centrally mounted at the top of a double inclined base or support j, webbing k being used which connects the ends of the vibrating part of the bellows with the ends of the base or support j.

Thus it will be seen that there are really six motors in all arranged in three pairs, and also so arranged, as shown in Fig. 1, that the valve of the first one is fully open, while the valve of the second one is partly open, and the valve of the third one entirely closed. Each half of the bellows is connected by a passage m with the interior of a trunk, so that to close passage by the grooved valve i the air contained therein must be sucked into the trunk or box t. n represents a partition parallel to the base j and separated therefrom by a series of upper and lower strips o. The base j, strips o and partition n are all perforated by the passage m. Passages p and q are likewise provided in the partition n, and the valve i is provided with two cut-away portions r and s. When the parts are in the position shown in Fig. 2, the upper part of the bellows g being expanded, to collapse same, the air is, of course, sucked into the box formed by the partition n, strips o and base j, and on the reverse motion, as the bellows expand, the air passes into same from the box a through the port o, as shown in the lower part of Fig. 2. t represents the box above referred to, and this box is connected by means of a pipe u with the wind-chest (not shown) in the ordinary manner, and a partial vacuum is maintained in any approved manner in said wind-chest.

In one of the corners of the box a is located a small box v, which contains the tempo valve w. The top of the box is open and the top of the box a, above the box v, is also open, as shown by dotted lines x in Fig. 1, these openings being closed by a board y screwed into the top of the box a. By unscrewing the board y access may be readily had to the tempo valve w.

The tempo valve w slides between guides 1 on the bottom of the box v, and between these guides the bottom of the box v is cut away, as shown by dotted lines at 2, the amount of the opening left unobstructed, being governed by the position of the tempo valve w.

3 represents a spring which holds the tempo valve to its seat, and 4 represents a wire running to the tempo lever (not shown) as may be operated by the performer. 5 shows in dotted lines, an opening in one of the ends of the box a leading into the interior of the box v, whereby communication between the atmosphere and the interior of the

box *a* is afforded by means of the opening 2, box *v* and opening 5.

In proximity to the opening 5 is located the automatic valve 6 pivotally connected at 5 its top to the top of the box *a*, and which serves to partly or wholly close the opening 5. This valve acts automatically in the following manner. 7 represents a bellows, connected at its lower part, by an opening shown 10 in dotted lines at 8, with the air pipe *u*, whereby the pressure in the pipe *u* is communicated to the bellows 7. The movable board of the bellows 7 is provided with an arm 8' rigidly attached thereto, and a link 9 15 is pivotally connected to the arm 8' and the lower edge of the valve 6, and, of course, the position of the arm 8' will govern the position of the valve 6, and a variance of the pressure in the bellows 7 will partially open 20 or close said valve. 10 represents a screw fastened at one end in the box *a*, and passing loosely through a perforation in the arm 8 and having a headed end which serves to limit the motion of the arm 8 in one direction. The bellows 7 is normally kept distended by means of a spring 11 bearing 25 against a stud 12 mounted in the movable side of the bellows. The other end of this spring is fastened to a pivoted board 13 pivoted on the projection 14 on the box *a*, which projection terminates in a sharp edge. 15 represents an adjusting screw passing through 30 the lower end of the board 13 and into the box *a*, whereby the tension of the spring 11 35 may be varied, as desired.

In re-rolling it is desirable that this should be done quickly, and for this reason I have provided a large opening 16, near the top of the box *a*, which is normally closed by 40 a valve 17 and a spring 18 bearing against said valve. 19 represents a wire leading to a lever (not shown) which may be operated by the performer to open the valve 17 during the act of re-rolling.

45 The operation is as follows: The air is exhausted from pipe *u* in the usual manner, and its tension of course varies with the rapidity with which the pedals are operated by the performer. The pipe *u* connects with the 50 wind chest and also through the port 8 with the interior of the governor bellows 7, so that the tension of the interior of the wind chest *t* and governor pneumatic 7 vary to the same degree as does the air tension in the pipe *u*. 55 Hence the motor runs fast or slow depending upon the amount of said tension. In order to prevent this variation and cause the motor to run at a substantially uniform speed, the governor pneumatic 7 is connected with 60 the valve 6 as already explained, so that when the tension in the air pipe *u* diminishes, the difference between said tension and atmospheric pressure on the outside of the removable board of the governor pneumatic 65 will cause an increased pressure on the re-

movable board of the governor pneumatic, and move it against the tension of the spring 11, which is capable of adjustment by the screw 15. This movement of the board will close the valve 6 and reduce the air tension in 70 the box *v*, and hence will reduce the pressure on the movable boards *g*, acting on the outside of the same. Hence it is evident that no matter how much the air tension in the pipe *u* varies that the difference between the air 75 tensions on both sides of the movable board *g* of the motors will remain substantially constant, and the motors will run at a constant speed independent of the air tension in the pipe *u*. While the motor speed is thus kept 80 constant, it may be varied from time to time by moving the lever which connects with the valve *w* so as to vary the opening of the port 2.

By my invention several distinct advantages are obtained. The motors are inclosed in a dust proof box which prevents them from collecting dust and also prevents the noise thereof from interfering with the music. The whole box is of a neat and ornamental 85 appearance, while further, by my constructions, the valves can be readily reached for cleaning or repairing without taking the whole thing to pieces. The valves 6 and 17 being outside of the box *a* can readily be 90 reached, and the valve *w* can also readily be reached by simply removing the board *y*.

Having thus described my invention, I claim—

1. In an auto-pneumatic motor for self-playing musical instruments, the combination of a motor, a source of power therefor an air-tight box inclosing said motor provided with an opening communicating with the atmosphere, a motor regulator consisting of a cut-off valve located over said opening in said box, a bellows connected with said source of power, and connections between said bellows and valve whereby the air pressure in said source of power governs the position of said valve, substantially as described. 100

2. In an auto-pneumatic motor for self-playing musical instruments, the combination of a motor, an air-tight box inclosing said motor and provided with an opening, an air pipe in communication with said motor a valve normally closing said opening, and means operated by the air pressure within said air pipe for automatically governing the 105 position of said valve, substantially as described. 115

3. In an auto-pneumatic motor for self-playing musical instruments, the combination of a motor, a source of power therefor an air-tight box inclosing the same and provided with an opening communicating with the atmosphere, a valve adapted to open or close said opening, a bellows operatively connected with said source of power, a spring for 110 normally holding said bellows distended, and 120

connections between said ~~device~~ ... said valve, whereby the air pressure in said source of power automatically governs the position of said valve, substantially as described.

- 5 4. In an auto-pneumatic motor for self-playing musical instruments, the combination of a motor, a source of power therefor an air-tight box inclosing said motor and provided with an opening communicating with 10 the atmosphere, a valve adapted to close said opening, means whereby the air pressure in said source of power will automatically vary the position of said valve, a second box within said first named box provided with an 15 opening leading into said first named box, and a tempo valve in said second named box adapted to slide over said last named opening, substantially as described.

5. In an auto-pneumatic motor for self-

playing musical instruments, the combination of a motor, a source of power therefor an air-tight box inclosing the same, said box being provided with an opening communicating with the atmosphere, a valve adapted to close said opening, means whereby the air 25 pressure in said source of power will govern the position of said valve, said box being provided with another opening communicating with the atmosphere, a spring-pressed valve normally closing said last named opening, 30 and a wire for operating said valve, substantially as described.

In testimony whereof, I affix my signature, in presence of two witnesses.
